UNITED STATES PATENT OFFICE.

CAMERON S. FITZHUGH, OF WACO, TEXAS.

FAN.

SPECIFICATION forming part of Letters Patent No. 696,426, dated April 1, 1902.

Application filed May 29, 1901. Serial No. 62,389. (No model.)

To all whom it may concern:

Be it known that I, CAMERON S. FITZHUGH, a citizen of the United States, residing at Waco, in the county of McLennan and State 5 of Texas, have invented certain new and useful Improvements in Fans; and I do hereby declare the following to be a full, clear, and exact description of the invention, such as will enable others skilled in the art to which it 10 appertains to make and use the same.

My present invention relates to improvements in fans, and more especially to automatic fans adapted to be placed upon a table or desk.

15 The objects of my invention are, first, to provide a device whereby the inclination of the fan may be adjusted to any desired position in the vertical plane; second, to provide means for allowing the fan to be adjusted to 20 any desired position in the horizontal plane; third, to provide a governor for maintaining a uniform speed of the fan regardless of the amount of power applied to the fan-shaft, and, fourth, to increase the efficiency and general construction of such a device.

25 In order that my said invention may be more fully described, reference is had to the accompanying drawings, in which the same parts are indicated by the same characters of 30 reference throughout the several views, in which—

Figure 1 represents a side elevation, partly in section, of a fan embodying my invention; and Fig. 2 is a similar view looking at the fan 35 in a line at right angles to the first view. Fig. 3 is an enlarged view showing the curvature of the bevel-gear in detail.

40 1 represents the main vertical shaft of the machine in the center of the standard *a*, carrying at its upper end the bevel-gear 2 and at its lower end the bevel-gear 3. This shaft is supported by the bearings 4 and 5. Meshing with the gear 3 is a bevel-gear 6, mounted upon a shaft 7, journaled in the base or stand- 45 ard.

45 8 is a gear-wheel carried by the shaft 7, meshing with the gear 9 upon the shaft 10, which in turn carries the gear 11, meshing with the gear 12, and so on through the gears 50 13, 14, 15, and 16. Gear 16 is mounted upon the shaft 17, which shaft also carries the bevel-gear 18. This bevel-gear 18 meshes

with the crown-shaped bevel-gear 19, loosely mounted upon the shaft 20, journaled in the bearings 21 22. This bevel-gear 19 carries a 55 pawl 23, adapted to engage with the ratchet 24. 25 is a coiled spring attached to the base *a* at its outer end and having its inner end secured to the shaft 20. Upon the lower end of the shaft 20 is rigidly secured the bevel-gear 26, adapted to mesh with the bevel-gear 27, carried by the shaft 28, mounted in bearings 29.

30 is a handle carried by the shaft 29, by which the spring may be wound. 65

The base or standard *a* is provided with the upwardly-extending curved arm *b*. The end of this arm *b* is provided with an overhanging bracket *c* and is threaded to receive the thumb-screw *d*. This bracket is drilled 70 out to receive the vertically-disposed stem *e*, the longitudinal axis of this stem being in a direct line with the axis of the vertical shaft 1. This stem is provided at its upper end with a set-collar *f* and at its lower end with 75 the socket *g*. This socket *g* is provided with an arc-shaped aperture, the radius of the arc being taken from the point *x* in the pitch-line of the gears 2 and 1.

h is a thumb-screw adapted to clamp the 80 curved arm *i* firmly in the socket *g*. This arm *i* is also formed on the arc of a circle struck from the point *x*.

j is a bearing formed upon the end of the arm *i*, in which is mounted the shaft *k*. This shaft 85 *k* carries the bevel-gear *l*, having its teeth curved in the arc of a circle struck from a point within the rotating axis of the gear in such manner that said gear is permitted to swing in the arc struck from the pitch-line of 90 the two gears without destroying the mesh of the same. Thus it will be seen that when the arm *i* is swung up or down to raise or lower the shaft *k* the meshing of the gears *l* and 2 will not be disturbed.

95 *m* is a fan mounted upon the shaft *k*, provided with fan-blades *n*.

o is a collar rigidly secured to the shaft *k*, in which are pivotally mounted the arms *p*, provided with the weighted ends or balls *q*. 100 These arms *p* are pivoted at the points *s* in the collar *o*, the ends *r* of these arms *p* being adapted to bear upon the adjacent end of the bearing *j* as the balls swing outward. One

or more springs *t* may be provided to connect these arms *p p* to retain the balls *q q* in a normally closed position.

The operation of the device is as follows:

- 5 Power having been applied to the shaft *1* by means of the spring *25* through the train of gearing hereinbefore described, it is transmitted from the bevel-gear *2* thereon to the curved-tooth bevel-gear *l*, causing the shaft *k* 70 to revolve the fan *m*. Fans as ordinarily constructed naturally run much faster when the spring has just been wound than when much of the power has been spent. This is prevented in my device by the employment 15 of the governor upon the shaft *k*. As the speed of the shaft *k* increases the arms *p p*, carrying the weighted ends *q q*, fly outwardly, causing the ends *r r* of the arms *p* to bind upon the round end of the bearing *j*, 20 thus keeping the speed of the fan uniform. When it is desired to swing the fan around to one side or the other in the horizontal plane to direct the air-blast in any desired direction, it is simply necessary to loosen the 25 thumb-screw *d* and swing the arm *i* around, the screw being again tightened when the desired position is attained. When it is desired to change the direction of the air-blast in the vertical plane—that is, to direct the 30 blast above or below the horizontal—the screw *h* is loosened, allowing the arm *i* to slide through the socket *g* and raise or lower the bearing *j*, carrying the shaft *k*, without interfering with or destroying the mesh of 35 the gears *l* and *2*.

f is an adjustable set-collar upon the upper end of the socket-stem *e*, and resting upon the top of the bracket *c* supports the socket *g* and insures the perfect mesh of the gears 40 when adjusted.

u is a set-screw adapted to engage the wheel 12 to stop the fan when desired.

It is obvious that many changes might be made in my invention without departing from 45 the spirit thereof, it being understood that I do not limit myself to the precise details herein shown.

Having thus described my invention, what I claim, and desire to secure by Letters Patent of the United States, is—

50 1. In a fan of the character described, the combination with a base, a bevel-gear centrally mounted upon a vertical shaft within said base, mechanism for operating said shaft, and an arm upon said base, carrying a bracket; 55 of an adjustable socket rotatably mounted in said bracket, a curved arm adjustably mounted in said socket, and a horizontally-disposed fan-shaft supported by said curved arm, carrying a gear adapted to mesh with the gear upon said vertical shaft, substantially as described.

2. In a fan of the character described, the combination with a base, a bevel-gear centrally mounted upon a vertical shaft within 65 said base, mechanism for operating said shaft, and an arm upon said base, carrying a bracket;

of an adjustable socket rotatably mounted in said bracket, a curved arm adjustably mounted in said socket, a horizontally-disposed fan-shaft supported by said curved arm, carrying a gear adapted to mesh with the gear upon said vertical shaft, and a centrifugal speed-governor mounted upon said fan-shaft, substantially as described. 70

3. In a fan, the combination with the base or standard, operating mechanism carried thereby, and an arm carried by said base; of a fan-shaft supported by said arm, mechanism for driving said fan-shaft, mechanism for 80 adjustably securing said fan-shaft in any desired position, and a centrifugal speed-governor carried by said fan-shaft for maintaining a uniform speed of the fan, substantially as described. 85

4. In a fan, the combination with the base, fan-operating mechanism carried thereby, and a bevel-gear mounted upon a vertical shaft in 90 said base and connected to said fan-operating mechanism; of a fan-shaft carrying a gear-wheel adapted to mesh with the gear-wheel upon said vertical shaft, and a curved arm for adjustably securing said fan-shaft in any desired position in both the horizontal and the vertical planes, without destroying 95 the mesh of the said gears, substantially as described.

5. In a fan, the combination with a base, fan-operating mechanism carried thereby, and a bevel-gear mounted upon a vertical shaft in 100 said base, and connected to said fan-operating mechanism; of a fan-shaft carrying a gear provided with curved teeth adapted to mesh with said bevel-gear upon the vertical shaft, a curved arm having an arc struck with its 105 center in the pitch-line of the two gears, and provided with a bearing for supporting the said fan-shaft, and means for adjusting the inclination of said fan-shaft, substantially as described. 110

6. In a fan, the combination with a base, fan-operating mechanism carried thereby, and a bevel-gear mounted upon a vertical shaft in 115 said base, and connected to said fan-operating mechanism; of a fan-shaft carrying a gear provided with curved teeth adapted to mesh with said bevel-gear upon the vertical shaft, a curved arm having an arc struck with its center in the pitch-line of the two gears, and provided with a bearing for supporting the 120 said fan-shaft, means for adjusting the inclination of said fan-shaft, and means for adjusting said shaft in the horizontal plane, substantially as described.

7. In a fan, the combination with a base, fan-operating mechanism carried thereby, and a bevel-gear mounted upon a vertical shaft in 125 said base, and connected to said fan-operating mechanism; of a fan-shaft carrying a gear provided with curved teeth adapted to mesh with said bevel-gear upon the vertical shaft, a curved arm having an arc struck with its center in the pitch-line of the two gears, and provided with a bearing for supporting the 130

said fan-shaft, means for adjusting the inclination of said fan-shaft, means for adjusting said shaft in the horizontal plane, and a governor upon said fan-shaft for controlling the speed of the fan, substantially as described.

8. In a fan, the combination with a base, a bevel-gear centrally mounted upon a vertical shaft within said base, and mechanism for operating said shaft; of a horizontally-disposed fan-shaft, a gear carried thereby, and an adjustable curved arm supporting said fan-shaft, the curvature of said arm being in an arc of a circle struck from the pitch-line of the two gears, substantially as described.

9. In a fan, the combination with a base, fan-

operating mechanism carried thereby, and a bevel-gear mounted in said base; of a fan-shaft carrying a gear-wheel adapted to mesh with the gear-wheel upon said vertical shaft, 20 and a curved arm, adapted to support said fan-shaft in any desired position in both the horizontal and vertical planes, the curve of said arm being in the arc of a circle struck from the pitch-line of the two gears, substantially as described. 25

In testimony whereof I affix my signature in presence of two witnesses.
